FIREPLACE IMPLEMENT SUPPORT

Jack Kraft, New York, N.Y., assignor to Centre Brass Works, Inc., New York, N.Y., a corporation of New York

Filed Apr. 22, 1957, Ser. No. 45,812

Term of patent 3½ years

(Cl. D33—17)

Fig. 1 is a front elevational view of a fireplace implement support, showing my new design.

Fig. 2 is a top plan view thereof.

Fig. 3 is a side elevational view thereof.

Fig. 4 is a rear elevational view thereof.

Fig. 5 is a plan view of the top support element, drawn to an enlarged scale.

The dominant feature of the design resides in the portion shown in full lines.

I claim:

The ornamental design for a fireplace implement support, substantially as shown and described.
